11 Claims. (Cl. 333—7)

This invention relates to microwave systems, especially waveguide plumbing, and more particularly to a switch therefor.

A waveguide switch may be used for transferring microwave energy from one input to either of two outputs, or to feed either of two outputs into a common transmission line, or in combination with a dummy load to feed a radar output to either an antenna or the dummy load. One general object of the present invention is to provide an improved waveguide switch for the foregoing and other purposes. A further object is to provide such a switch which is light in weight and suitable for airborne equipment.

More particular objects are to provide a waveguide switch which is compact, fast in operation, dynamically balanced, and which has good isolation, and a voltage standing wave ratio which is low.

A further object is to provide a waveguide switch the relatively movable or internal flanges of which conform to the surface of a sphere, thus simplifying the production of chokes in said flanges, and making possible a more compact assembly of oppositely directed chokes for the inside and outside flanges.

Further objects center about the motor mechanism to operate the switch under remote control. In preferred form we employ a rotary solenoid and improved linkage between said solenoid and the movable part of the switch. In accordance with features and objects of the invention this linkage steps up the motion from 90° to 180°, provides gradual acceleration and deceleration, and is self-locking in its end positions. Additional means may be provided to reduce the energization of the solenoid when it is left energized.

A further object of the invention is to provide a shorting or isolation plate which acts also as a counterbalance for balancing the rotor of the switch. The rotor is of the L type, having an H plane bend, but made compact by using a sharp corner and a mitred wall.

To accomplish the foregoing objects, and such other objects as will hereinafter appear, our invention resides in the waveguide switch elements, and their relation one to another, as are hereinafter more particularly described in the following specification. The specification is accompanied by drawings, in which:

Fig. 1 is a perspective view showing a waveguide switch embodying features of our invention;

Fig. 2 is a longitudinal section through the waveguide switch taken approximately in the plane of the line 2—2 of Fig. 1;

Fig. 3 is a transverse section taken approximately in the plane of the line 3—3 of Fig. 2;

Fig. 4 is a partially sectioned fragmentary view of the housing of the switch;

Fig. 5 is a view of the rotor alone, looking toward its movable spherically surfaced outlet flange;

Fig. 6 is a section through one of the stationary outlet

2

flanges, taken on a diameter perpendicular to the section shown in Fig. 2;

Fig. 7 is explanatory of the location of the roller bearings for the rotor;

Fig. 8 is a view looking toward the inside face of one of the stationary outlet flanges; and

Fig. 9 is a wiring diagram.

Referring to the drawing, and more particularly Figs. 1 and 2, the waveguide switch comprises a hollow body 12 having an inlet flange 14 and two spaced outlet flanges 16 and 18. There is also a waveguide L generally designated 20 housed in the body 12, and mounted for rotation about the axis 22 (Fig. 2) of one of the two arms of the L; in this case the arm 24. This axis 22 is also the axis of the inlet flange 14. The L 20 has an H bend, as will be seen from inspection of Fig. 1.

In the preferred form of the invention shown the two spaced outlet flanges 16 and 18 are parallel to one another and are both perpendicular to the inlet flange 14, so that they are in right-angled T relation. The rotor or L 20 is made compact by using a sharp or perpendicular inside corner at 26, and a wall 28 which is at an angle of 135° to the arms 24 and 30 of the L.

The inlet arm 24 of the L is preferably provided with a cylindrical bearing portion 32, and this is preferably made large enough in diameter to permit the provision of a choke 34 located outside the waveguide. The free end 36 of the outlet arm 30 of the L is preferably convex and conforms to the surface of a sphere which has its center at the intersection of the axes of the arms 24 and 30 of the L. The inner face 38 of outlet flange 16 and the inner face 40 of outlet flange 18 are preferably concavely spherical to conform to the convexly spherical end 36 of the L. This is shown in Fig. 6 by the radius R. In Fig. 6 it will be noted that the inner face 38 may be provided with a choke 42, while the outer face may be provided with a choke 44. The same applies to the other outlet flange 18 shown in Fig. 2. The outer chokes 44 are cylindrical. The inner chokes 42 (Fig. 6) are defined on the frustum of a cone, the apex of which coincides with the center of the spherical surface. The chokes 42 are made frusto-conical primarily for a reason explained later, but it will be seen in Fig. 6 that one advantage is that the chokes 44 and 42 may be moved into compact relation.

The rotor or L is preferably provided with a shorting or isolation plate 46 (Fig. 2) secured by means of screw 48 to a boss 50 formed on the angular wall 28 of the rotor. This isolation plate is preferably made sufficiently weighty to counter-balance the arm 30 of the L, so that it serves as a balance in addition to its electrical function of shorting the disconnected outlet flange, in this case the flange 18. The periphery of the isolation plate 46 is made to conform to the surface of a sphere having its center at the intersection of the axis of the L, as previously described for the surfaces 36, 38 and 40.

The L 20 is preferably rotatably supported at both ends. For this purpose the L is provided with a journal 52 received in a ball bearing 54 carried by a stationary bearing wall 56 forming a part of the housing 12. At the other end of the L the cylindrical inlet flange portion 32 is preferably supported on anti-friction bearings. Specifically, we employ four small rollers located at the corners of a square, as is indicated by the rollers 58 in Fig. 7, which support the cylindrical flange 32. The mounting of these rollers is shown in Fig. 4. They are received on bearing studs 60 secured to the large stationary inlet flange 14 of housing 12. The rollers 58 may be and preferably are small roller bearings the outer races of which are used as the rollers which support the L.

Reverting now to Fig. 2, the L is turned by a suitable

motor means, preferably a rotary solenoid indicated at 62. This drives the L through linkage terminating at the journal 52. The linkage is best shown in Fig. 3, referring to which the rotary solenoid 62 turns a driving arm 64 through an angle of substantially 90°. The free end of driving arm 64 is movable in a slot 66 disposed longitudinally of an intermediate arm 68, pivoted at a point 70 which is spaced from the axis 72 of the rotary solenoid. The free end of this intermediate arm 68 slidably engages a slot 74 in a driven arm 76, which is secured directly on the journal 52 of the rotor.

In the specific arrangement shown the parts are so proportioned that a motion of 90° by the driving arm 64, produces a motion of 180° of the driven arm 76, and what is equally important, the 180° motion is characterized by a gradual acceleration at the beginning and a corresponding gradual deceleration at the end. This is highly desirable for the present purpose, because of electrical reasons which will be described later. It will be observed also that the arms 64 and 68 are in substantially perpendicular relation at the beginning and end of their motion, thus helping make the linkage self-locking against disturbance from without.

The connection between arm 64 and slot 66 is preferably made by means of an anti-friction roller 78, and this may be a small ball bearing the outer race of which acts as the roller. Similarly the connection between arm 68 and slot 74 may be made by means of an anti-friction roller 80, which again may be a ball bearing the outer race of which acts as the roller. The rotary solenoid 62 may be of conventional type, that here shown being made by G. H. Leland Inc. of Dayton, Ohio under the name "Ledex".

The stationary flanges 16 and 18 have cylindrical walls at 82 which are received in mating cylindrical sockets in the housing 12. One of these sockets is shown at 84 in Fig. 4. The flanges may be sealed to the housing as by the use of gaskets 86 shown in Fig. 2. The parts may be held together by assembly screws the heads of which are shown at 87 in Fig. 1. For pressurized systems the flanges 16 and 18 may have annular slots 88 to receive O rings or other suitable gaskets. Similarly the stationary inlet flange 14 may have an annular slot 90 for an O ring or other gasket. The back end of the housing is closed by means of a plate 92, and a pressure sealing gasket 94 may be employed. Connections for the control wiring may be made through a suitable JAN type connector, here indicated at 96, to maintain the pressure seal.

The configuration of the stationary outlet flanges 16 and 18 will be clear from examination of Figs. 6 and 8 of the drawing. The cylindrical outside choke 44 (Fig. 6) may extend entirely around the waveguide. The conical inside choke is preferably interrupted at the ends of the waveguide, as is best shown in Fig. 8, but also appears in Fig. 6. For compactness, the periphery of the flange 18 has three flats 19, as shown in Fig. 8.

The rotor or L is shown in Fig. 5 looking toward the spherically surfaced outlet flange 36. The remote waveguide wall 24, and the sloping wall 28, are visible through the rectangular waveguide opening. Journal 52 is secured to wall 28 at 98, as by means of welding, and the location of boss 50 is also shown. If made in sufficient quantity the L may be cast, but in the present case it is assembled out of pieces which are welded together. Specifically, two pieces of rectangular waveguide 24 and 30 are cut or mitered on a 45° angle, as is indicated by the line 100 in Fig. 2, and are welded together. (The term "welded" is intended to include soldering and brazing, etc.) The outside corner is cut away and replaced by the wall 28 to which the boss 50 and journal 52 are welded. Wall 28 is welded in place. The spherically surfaced flange 36 is welded at the free end of the waveguide

arm 30, and the cylindrical flange 32 is welded at the free end of the waveguide arm 24.

One wiring arrangement for control of the switch is shown in Fig. 9, in which the solenoid coil is indicated at 62, and is energized from any suitable power line source 102. A switch 104, which may be an ordinary toggle switch, is used to control the waveguide switch. The solenoid has its own internal spring which urges it to one end position. When switch 104 is closed solenoid 62 is energized, thereby changing the waveguide switch to opposite end position. If desired, microswitches may be provided for additional purposes, and referring to Fig. 3, in the present case there are two microswitches 106 and 108. One or the other of these is reached and shifted by the driven arm 76.

Reverting now to Fig. 9, one purpose for which the microswitches may be used is to operate pilot lamps to show the position of the waveguide switch. Microswitch 106 may light a pilot lamp 110, while microswitch 108 may light a pilot lamp 112. The lamps may differ in color.

Another purpose for which one of the microswitches may be used is to greatly reduce the energization of the solenoid coil 62 after it has moved the waveguide switch. More current is needed to initiate the solenoid operation, than to hold the solenoid after its core has been pulled home. We accordingly prefer to provide a current reducing resistor 114 in shunt with normally closed contacts of microswitch 106, so that when the microswitch is operated it opens the direct circuit to solenoid 62, after which the solenoid current must flow through resistor 114, and is thus reduced in value.

Either or both microswitches may be used for other outside control purposes, as, for example, to start or stop microwave equipment connected to the waveguide switch.

The body or housing 12 of the switch (see Fig. 4) is preferably cast of aluminum in order to keep the switch light in weight. The stationary flanges 16 and 18 may also be made of aluminum.

It was previously mentioned that the linkage has the advantage of gradual acceleration and deceleration. This is important in order to obtain rapid switching. In the present case the switch requires only one-tenth of a second to operate. The true operating time includes any time during which the rotor vibrates or chatters at the end of its movement, for the transmission of radar or other microwave energy is spoiled during any such vibration or chatter. Thus a different switch mechanism might change the switch in less time, and yet the true total switching time, from the viewpoint of effective transmission of microwave energy, might be much longer than the time used for the mechanical movement alone. In the present case there is no significant vibration or chatter, and the time used for the mechanical movement corresponds to the switching time.

It has previously been pointed out that the chokes 42 are preferably frusto-conical in configuration. It is primarily for this reason that spherical rather than cylindrical surfaces are employed at 36, 38 and 40 (Fig. 2). With a cylindrical surface the chokes would require a configuration which would be extremely difficult and expensive to machine. However, with the spherical surfaces here employed the chokes 42 (Fig. 6) may be frusto-conical, and that in turn is a shape very easy to form in a milling machine by using an angularly disposed shaft for the milling machine cutter, accompanied by rotation of the flange about its own axis.

It is believed that the construction and operation, as well as the advantages of our improved waveguide switch, will be apparent from the foregoing detailed description. The particular switch shown has a VSWR (voltage standing wave ratio) of less than 1.10; an isolation greater than 60 db; will take pressurization up to 60 lbs. per square inch; and has a radio frequency switching time of about one-tenth second.

It will be apparent that while we have shown and described our invention in a preferred form, changes may be made in the structure shown without departing from the scope of the invention, as sought to be defined in the following claims. In the claims the terms "inlet" and "outlet" are used for convenience, but it will be understood that the microwave energy may flow through the L of the switch in opposite direction, as, for example, if one or another of two different transmitters is to be connected at will to a common antenna. The terms T and L are intended to include an arrangement in which the axes are at an angle greater than 90° , although the 90° angle shown is most convenient for practical purposes, and some claims specify the preferred perpendicular arrangement of the flanges. The motion of the rotor need not necessarily be 180° , for in theory there might be outlet flanges which are angularly related instead of parallel, and which might correspond to a motion of the rotor of only, say, 120° or 90° , instead of 180° , although the latter is most convenient, and is specified in some of the claims.

We claim:

1. A waveguide switch comprising a hollow body having an inlet flange and two spaced outlet flanges parallel to one another and both perpendicular to the inlet flange in T relation, a waveguide L housed in said body and mounted for rotation about the axis of one of the two arms of the L coinciding with the axis of the inlet flange, the inlet end of said L having a cylindrical bearing portion, and the free end of the outlet arm of said L being convex and conforming to the surface of a sphere having its center at the intersection of the axes of the L , the inner face of each outlet flange being concavely spherical to conform to the convexly spherical end of the L , said inner face of said outlet flange having a choke defined on the frustum of a cone the apex of which coincides with the center of the spherical surface.

2. A waveguide switch comprising a hollow body having an inlet flange and two spaced outlet flanges parallel to one another and both perpendicular to the inlet flange in T relation, a waveguide L housed in said body and mounted for rotation about the axis of one of the two arms of the L coinciding with the axis of the inlet flange, the inlet end of said L having a cylindrical bearing portion with a cylindrical choke outside the waveguide, and the free end of the outlet arm of said L being convex and conforming to the surface of a sphere having its center at the intersection of the axes of the L , the inner face of each outlet flange being concavely spherical to conform to the convexly spherical end of the L , said inner face of said outlet flange having a choke defined on the frustum of a cone the apex of which coincides with the center of the spherical surface, the outer face of said outlet flange having a cylindrical choke.

3. A waveguide switch comprising a hollow body having an inlet flange and two spaced outlet flanges, a waveguide L housed in said body and mounted for rotation about the axis of one of the two arms of the L coinciding with the axis of the inlet flange, said L having an H bend with its walls mitred, the inside corner being a right angle, and the outside corner having a wall at an angle of 135° to the arms of the L and a shorting or isolation plate secured to said L and shaped to conform to the inner face of the flange opposite the outlet arm of the L , said isolation plate being located at one outlet flange when the outlet arm of the L is at the other outlet flange.

4. A waveguide switch comprising a hollow body having an inlet flange and two spaced outlet flanges parallel to one another and both perpendicular to the inlet flange in T relation, a waveguide L housed in said body and mounted for rotation about the axis of one of the two arms of the L coinciding with the axis of the inlet flange, and a shorting or isolation plate secured to said L and shaped to conform to the inner face of the flange opposite the outlet arm of the L , said isolation plate being

located at one outlet flange when the outlet arm of the L is at the other outlet flange said isolation plate being made sufficiently weighty to counterbalance the outlet arm of the L for balanced rotation of the L about the axis of the inlet arm.

5. A waveguide switch comprising a hollow body having an inlet flange and two spaced outlet flanges parallel to one another in T relation, a waveguide L housed in said body and mounted for rotation about the axis of one of the two arms of the L coinciding with the axis of the inlet flange, a rotary solenoid for operating said L , and linkage between said rotary solenoid and said L , said linkage comprising a driving arm on the rotary solenoid having its free end movable in a slot disposed longitudinally of an intermediate arm pivoted at a point spaced from the axis of the rotary solenoid and spaced from the axis of rotation of the L , and a driven arm secured to the L on the axis of rotation of the L , the free end of said intermediate arm slidably engaging a slot disposed longitudinally in the driven arm.

6. A waveguide switch comprising a hollow body having an inlet flange and two spaced outlet flanges parallel to one another in T relation, a waveguide L housed in said body and mounted for rotation about the axis of one of the two arms of the L coinciding with the axis of the inlet flange, a rotary solenoid for operating said L , and linkage between said rotary solenoid and said L , said linkage comprising a driving arm on the rotary solenoid having its free end movable in a slot disposed longitudinally of an intermediate arm pivoted at a point spaced from the axis of the rotary solenoid, and a driven arm secured to the L on the axis of rotation of the L , the free end of said intermediate arm slidably engaging a slot disposed longitudinally in the driven arm, the arrangement being such that a motion of about 90° of the driving arm produces a motion of 180° of the driven arm with gradual acceleration and deceleration.

7. A waveguide switch comprising a hollow body having an inlet flange and two spaced outlet flanges parallel to one another in T relation, a waveguide L housed in said body and mounted for rotation about the axis of one of the two arms of the L coinciding with the axis of the inlet flange, a rotary solenoid for operating said L , and linkage between said rotary solenoid and said L , said linkage comprising a driving arm on the rotary solenoid having its free end movable in a slot disposed longitudinally of an intermediate arm pivoted at a point spaced from the axis of the rotary solenoid, and a driven arm secured to the L on the axis of rotation of the L , the free end of said intermediate arm slidably engaging a slot disposed longitudinally in the driven arm, and said driving and intermediate arms being disposed at right angles in their terminal positions so that the linkage is self-locking.

8. A waveguide switch comprising a hollow body having an inlet flange and two spaced outlet flanges parallel to one another in T relation, a waveguide L housed in said body and mounted for rotation about the axis of one of the two arms of the L coinciding with the axis of the inlet flange, a rotary solenoid for operating said L , and linkage between said rotary solenoid and said L , said linkage comprising a driving arm on the rotary solenoid having its free end movable in a slot disposed longitudinally of an intermediate arm pivoted at a point spaced from the axis of the rotary solenoid, and a driven arm secured to the L on the axis of rotation of the L , the free end of said intermediate arm slidably engaging a slot disposed longitudinally in the driven arm, the arrangement being such that a motion of about 90° of the driving arm produces a motion of 180° of the driven arm with gradual acceleration and deceleration, and said driving and intermediate arms being disposed at right angles in their terminal positions so that the linkage is self-locking.

9. A waveguide switch comprising a hollow body hav-

ing an inlet flange and two spaced outlet flanges parallel to one another and both perpendicular to the inlet flange in T relation, a waveguide L housed in said body and mounted for rotation about the axis on one of the two arms of the L, coinciding with the axis of the inlet flange, the inlet end of said L having a cylindrical bearing portion, the free end of the outlet arm of said L being convex and conforming to the surface of a sphere having its center at the intersection of the axes of the L, the inner face of each outlet flange being concavely spherical to conform to the convexly spherical end of the L, and a shorting or isolation plate secured to said L and shaped at its periphery to conform to the concavely spherical inner face of the flange opposite the outlet arm of the L, said isolation plate being located at one outlet flange when the outlet arm of the L is at the outer outlet flange.

10. A waveguide switch comprising a hollow body having an inlet flange and two spaced outlet flanges parallel to one another and both perpendicular to the inlet flange in T relation, a waveguide L housed in said body and mounted for rotation about the axis of one of the two arms of the L, coinciding with the axis of the inlet flange, the inlet end of said L having a cylindrical bearing portion, the free end of the outlet arm of said L being convex and conforming to the surface of a sphere having its center at the intersection of the axes of the L, the inner face of each outlet flange being concavely spherical to conform to the convexly spherical end of the L, said inner face of said outlet flange having a choke defined on a frustum of a cone the apex of which coincides with the center of the spherical surface, and a shorting or isolation plate secured to said L and shaped at its periphery to conform to the concavely spherical inner face of the flange opposite the outlet arm of the L, said isolation plate being located at one outlet flange when the outlet arm of the L is at the

other outlet flange said isolation plate being made sufficiently weighty to counterbalance the outlet arm of the L for balanced rotation of the L about the axis of the inlet arm.

5 11. A waveguide switch comprising a hollow body having an inlet flange and two spaced outlet flanges parallel to one another and both perpendicular to the inlet flange in T relation, a waveguide L housed in said body and mounted for rotation about the axis on one of the two arms of the L, coinciding with the axis of the inlet flange, the inlet end of said L having a cylindrical bearing portion, the free end of the outlet arm of said L being convex and conforming to the surface of a sphere having its center at the intersection of the axes of the L, the inner face of each outlet flange being concavely spherical to conform to the convexly spherical end of the L, said inner face of said outlet flange having a choke defined on the frustum of a cone the apex of which coincides with the center of the spherical surface, said L having an H bend with its walls mitered, the inside corner being a right angle and the outside corner having a wall at an angle of 135° to the arms of the L.
